Primary Examiner—Dominic Simone*(74) Attorney, Agent, or Firm*—Marshall A. Lerner; Kleinberg & Lerner, LLP**CLAIM**

The ornamental design for a flap on shoe tongue, as shown and described.

DESCRIPTION

FIG. 1 is a perspective view of a flap on shoe tongue embodying my new design;

FIG. 2 is a left side view thereof;

FIG. 3 is a right side view thereof;

FIG. 4 is a top plan view thereof; and,

FIG. 5 is a front side view thereof.

The broken line showing of the shoe in the figures is for illustrative purposes only and forms no part of the claimed invention.
